(57) **CLAIM**

The ornamental design for a temporary instrument holder, sharps protector, passing aid and safety transport apparatus, as shown and described.

DESCRIPTION

FIG. 1 is a front perspective view of a temporary instrument holder, sharps protector, passing aid and safety transport apparatus showing my new design;

FIG. 2 is a left side view thereof;

FIG. 3 is a front view thereof;

FIG. 4 is a back view thereof;

FIG. 5 is a top view thereof;

FIG. 6 is a bottom view thereof; and,

FIG. 7 is another front perspective thereof.

Any broken lines illustrative of environmental structure in the drawings are not part of the design sought to be patented.
